DEVICE FOR HOLDING AND CURLING HAIR

Anna E. Farrell, Seattle, Wash.

Application December 23, 1938, Serial No. 247,397

2 Claims. (Cl. 132—40)

This invention relates to devices for holding and curling hair, and particularly to such a device formed from a pair of hair pins slidably connected therefor.

5 An object of the invention is to provide improvements upon and over devices described in Letters Patent of the United States No. 2,102,687, issued to me December 2, 1937, and to provide a device of light wire of few parts, and simpler 10 and cheaper in construction than devices previously in use, and which will be more effective in operation.

A particular object is to provide a device, formed of inexpensive material, comprising a 15 pair of bent wire hair pins one wider between the legs than the other, and slidably connected together, whereby a lock of hair may be bound and rolled for curling, and then expanded, and latched on the head, and retracted in dimensions 20 for easy removal from the curl without disturbing such curl formation.

A further object is to provide a flexible device for gathering loose hair and for winding and binding the same in rolls for curl formations. 25 The said device preferably formed of a pair of members similar to open ended hair pins for holding hair, but one of said members with legs thereof spaced wider apart relatively than the legs of the other, and positioned outside the narrower spaced legs, with eyes on the free ends 30 of the legs of the said outer and wider pin, and the legs of the inner and narrower pin slidably mounted through said eyes, said outer member of substantially elongated U form and the inner 35 pin of substantially elongated V form, whereby the outer legs will be expanded apart, and retracted toward each other when said inner legs are moved to and fro in said eyes, respectively.

With these and other objects, that may be 40 hereinafter shown, I have illustratively exemplified my invention by the accompanying drawing, of which:

Figure 1 represents a diagrammatic view, with pins within rolls of hair in place on a head.

45 Figure 2 represents an edge view of the two pins together, and the end of a lock of hair as first positioned for winding.

Figure 3 represents an elevation of the assembled pins, in closed position for latching a 50 roll or curl of hair between the same.

Figure 4 represents a cross section of the pins taken on line 4—4 of Fig. 3, with ends of the inner pin removed.

55 Figure 5 represents an elevation of the two pins, with a lock of hair wound over the larger pin,

and the inner pin withdrawn to position for inserting the point thereof beneath the roll of hair to prevent the same from unwinding, and the outer end of the inner pin broken away.

Figure 6 represents a top plan of the device, 5 in position on the side of a head, with a lock of hair rolled thereover, and the inner pin point projected beneath the hair and over the loop end of the larger pin, for retaining the roll of hair in position for a curl, and dotted line indicating the position of the inner pin when used 10 for picking up loose hair along the scalp after the roll has been formed over the device.

Like characters on the different figures represent like parts. The letter A, represents an outer hair pin member substantially in elongated U, 15 formation, and B, represents an inner member or hair pin substantially elongated V, in form, and longer than the outer member. Both pins are preferably constructed of light flexible wire, 20 which may be cut in suitable lengths from any source of supply, without any waste. The material being subject to shaping by bending, and to then retain such shapes normally, from inherent 25 resiliency thereof, for which steel with semi spring action has been found suitable. The gauge of the wire need be no greater than one thirty second of an inch, and may be less, and when used in the hair on a head is practically 30 invisible, and may be carried in place, both day and night without discomfort.

The outer pin is formed with a rounded head or 35 loop 7, for convenient use in the hair, and the legs 8 thereon are projected back a suitable distance practically parallel with each other normally. At the free ends of the legs are built 40 eyes 9, preferably arranged at right angles with the legs and projected inward toward each other, and preferably slightly oblong, but with sufficient diameter at the narrowest central position to freely receive operative legs 11, slidably therein 45 of an inner pin B. This inner pin is closed at the head end 12 by a sharper bend than the outer head 7, to provide for insertion under or through a mass of hair; but presents a rounded point which may be pressed against the scalp without 50 injury thereto, when necessary to gather up all the desired hair thereover. The legs 11 are projected back from the head end 12 in diverging directions, and are slidably threaded or mounted through the eyes 9, and are extended beyond such eyes sufficiently to provide a handle 13, for manipulating the device. The extended tips thereof, are preferably rounded toward each other and closed as by a weld 14, to prevent the 55

two members or pins from becoming separated or lost from each other, and to prevent any stray hairs becoming tangled between such legs, or tips thereof.

5 The projection of the legs outward beyond the eyes, is more specially provided, to permit the head end to move forward, above or beneath, the rounded head 12 of the outer pin, for locking or latching a quantity of hair between the 10 pins. The oval shape of the eyes facilitates lateral movement of the pairs of legs, for gathering hair between the same, and for clamping the same for curls, or for retaining the same in other desired forms. The side walls of the eyes provide 15 fulcrums for such lateral actions, and the front and rear walls of the eyes provide guides for the inner legs when moved forward or backward therein.

20 Indents or corrugations as 10 may be provided along the legs of the outer pin, for retaining the device in positions within a roll or coil of hair. It will be understood that when the inner V shaped or positioned legs 11, are pressed forward through the eyes 9, that the side legs of the 25 outer pin and corrugations along the same may be expanded within a coil of hair by the widening of legs 11. Again, when the inner pin is drawn outward, the narrowing of the inner legs, draws the outer legs toward each other, to facilitate the easy removal of the device from a roll or curl of hair, without disturbing the formation thereof. The expansion or widening of the side legs of the outer pin, is important for stretching a mass or coil of hair tightly around the device, 30 whereby the set of the hair in curl formation is improved and facilitated.

35 In use the operator, preferably partially withdraws the inner pin from the eyes, and depresses the point 12 and positions the same beneath the 40 end of a lock of hair d, and then raises such point and clamps such hair end between both pins in parallel positions. The two pins are then rotated until the lock of hair is rolled around the device in close proximity to the head C. The 45 inner pin is then sufficiently withdrawn to free such hair, and then extended laterally, as indicated in dotted lines 11' Fig. 6, and the point moved along the scalp in form indicated in 12', thus gathering all hairs beneath the roll of hair, 50 meanwhile the inner pin is pressed forward along the scalp until the point thereof is adjacent and opposite to the closed end 7 of the outer pin. The flexible pins are then bent or flexed so that the

inner point may be projected over and beyond the loop 7, thus effectually binding the hair within or between the two pins, and outside of the loop or curl of hair is positioned over the device, as indicated in Figs. 1 and 6. In event of such 5 position with a heavy roll of hair, the device may be rendered generally invisible, while the curl is becoming set by the device, in expanded condition. On withdrawal of the inner pin as indicated in Fig. 5 the outer legs are drawn 10 toward each other, thus narrowing the device, and facilitating the removal thereof from the curl.

15 Other methods of use may be suggested by ladies familiar with attempts at forming curls, and holding hair by pins, and while I have illustrated definite structure for a device, I do not limit my invention thereto, but desire to protect my invention broadly within the scope of the 20 claims, and disclosures.

25 Having described my invention, I claim as new:

1. A device for holding, stretching, and curling hair, comprising, an outer and an inner pair of legs, said outer pair of legs in substantially elongated U formation, open eyes on the free 30 ends of the legs of such outer pair, said inner pair of legs in substantially elongated V formation, and greater in length than said outer pair, and slidably mounted through said eyes, 35 and adapted for lateral and horizontal movements for binding the end of a lock of hair against said outer legs, and for expanding and retracting the space between said outer legs for tightening and loosening said outer legs within a coil of hair, and further adapted for latching one side of a roll of hair between said two pairs of legs and close to the head and scalp adjacent said hair.

40 2. A device of the structure described in the foregoing claim, with corrugations along said outer pair of legs, adapted to be driven outward into a roll of hair thereover when said outer legs are expanded and to prevent said device from shifting within a roll of hair thereover, the ends 45 of said inner legs projected outward from said eyes, for handles for manipulating the device, and the outer tips of said inner legs attached together to prevent hairs from entering between the legs thereof and to prevent the separation and loss of one of said pair of legs from the other.

ANNA E. FARRELL.
